INSOLE AND PROCESS OF MAKING SHOES
THEREWITH

William H. Bain, University City, Mo.

Application August 19, 1932. Serial No. 629,420

5 Claims. (Cl. 12—142)

This invention relates to the manufacture of shoes, and has for its principal object to provide a shoe with an insole having a relatively thin and flexible forepart and a removable backing 5 therefor to hold the parts to shape during the lasting operation. The invention consists in the insole and in the process hereinafter described and claimed.

In the accompanying drawings, which form 10 part of this specification and wherein like symbols refer to like parts wherever they occur,

Figs. 1, 2 and 3 are, respectively, an inner face view of the relatively thin and flexible forepart, the relatively thick and inflexible shank piece, 15 and the forepart backing piece which form the insole embodying my invention,

Fig. 4 is an inner face view, showing the relatively thin and flexible forepart of the insole permanently cemented to the relatively thick 20 and inflexible shank piece thereof,

Fig. 5 is an outer face view of the insole with the forepart backing piece removably secured thereto,

Fig. 6 is a longitudinal section through the 25 insole on the line 6—6 in Fig. 5,

Fig. 7 is a longitudinal section showing the insole tacked to the bottom of the last after being molded to conform to the surface thereof,

Fig. 8 is a plan view showing the upper lasted 30 to the insole,

Fig. 9 is a vertical cross-section on the line 35 9—9 in Fig. 8,

Fig. 10 is a similar section on the line 10—10 in Fig. 8,

Fig. 11 is a view similar to Fig. 8, showing the 40 lasting tacks pulled, the metal shank and the filling material applied and the outsole laid,

Fig. 12 is a longitudinal section through the 45 shoe, showing the same removed from the last and the forepart backing piece partly removed from the shoe,

Fig. 13 is a bottom plan view of the shoe, showing the outsole stitched to the insole and upper,

Fig. 14 is a transverse section through the 50 forepart of the shoe on the line 14—14 in Fig. 13,

Fig. 15 is a similar section through the shank portion of the shoe on the line 15—15 in Fig. 13; and

Fig. 16 is a longitudinal section through the 55 finished shoe.

The insole used in my process of making shoes comprises a forepart A of relatively thin flexible leather, a shank piece B of relatively thick and inflexible ordinary insole leather, and a relatively thin forepart backing piece C of a mate-

rial such as fiber, having a greater stiffness and tensile strength than the thin leather forepart A. The forepart A and shank piece B of the insole have their adjacent ends skived, overlapped and permanently secured together, preferably by 60 means of cementing material 1; and the fiber forepart backing piece C is temporarily secured to the outer face of said forepart by cementing material 2, the shank end of said fiber forepart backing piece being preferably left free from said 65 shank piece so as to facilitate its removal.

The insole thus formed is placed in a molding form (not shown) and shaped to conform to the bottom surface of the last D to which it is to be secured. The molded insole is then placed on the 70 last D with the removable fiber forepart backing piece C engaging the bottom surface thereof, the insole being temporarily held on the last by tacks 3. A suitable cementing material 5 is then applied to the edges of the insole and the shoe upper 75 E and the upper lasted to the insole. The front lasting allowance of the upper is secured to the insole by means of tacks 6 that are driven only part way into the last, while the heel lasting allowance of the upper is secured to the insole by 80 tacks 6a that are clinched on the inner face of the insole by means of a metal heel plate 7 fixed to the bottom of the last. The usual metal shank stiffener 8 is then tacked to the inner face of the insole, after which a filling 9 of cotton or the 85 like is placed in the bottom of the forepart of the shoe to obtain an even surface for the foot.

After the cement 5 that holds the upper to the insole sets, the tacks 3 and 6 are pulled out. The lasting allowance of the upper is then smoothed, 90 an outsole F is laid and temporarily held by any suitable means, as by cement 10, and the last is then pulled out of the shoe. The removable fiber forepart backing piece C is then pulled out of the shoe, and the outsole is then permanently secured 95 in place by a row of stitching 11 that passes through the upper and insole.

It is noted as an important advantage of my invention that it provides a strong and durable lightweight shoe that has extreme flexibility in 100 the forepart of its sole. It is also noted that the removable fiber forepart backing piece of the insole has a relatively high tensile strength and thus serves to prevent buckling and stretching of the relatively thin and flexible leather forepart 105 during the lasting operation.

Obviously, the invention admits of various changes and I do not wish to limit myself to the operations hereinbefore described. For instance, the process is also applicable to shoes whose out- 110

soles are not stitched to the uppers but only cemented, such cementing being done while the shoe is on the last.

What I claim is:

- 5 1. An insole comprising a forepart of relatively thin and flexible material, a shank piece of relatively thick and inflexible material, and a backing piece removably secured to said forepart, said backing piece being made of a material having a greater tensile strength and stiffness than said forepart.
- 10 2. An insole comprising a forepart of relatively thin and flexible leather, a shank piece of relatively thick and inflexible leather, means permanently securing said forepart and shank piece together, and a backing piece removably secured to said forepart, said backing piece being made of a material having a relatively high tensile strength and relatively high resistance to buckling.
- 15 3. An insole comprising a shank piece of relatively thick and inflexible material, a forepart of relatively thin and flexible material, and a backing piece of relatively stiff material of relatively high tensile strength removably secured flatwise to the inner face of said relatively thin and flexible forepart to prevent stretching or buckling thereof, the rear portion of said backing piece overlapping the inner face of the forward portion

30

of said shank piece and being left loose to facilitate removal thereof from said forepart.

4. The process of making shoes having an insole with a relatively thick and inflexible shank piece and a relatively thin and flexible forepart of single thickness which comprises temporarily securing to the forepart of said insole a backing piece of relatively greater tensile strength and stiffness than said forepart, placing said insole on a last with said backing piece in engagement therewith, cementing a shoe upper to said insole, laying on an outsole, removing said last and said backing piece and then sewing said outsole to said upper and said shank piece.

5. The process of making shoes having an insole with a relatively thick and inflexible shank piece and a relatively thin and flexible forepart of single thickness which comprises temporarily securing to the forepart of said insole a backing piece of relatively greater tensile strength and stiffness than said forepart, placing said insole on a last with said backing piece in engagement therewith, cementing a shoe upper to said insole, laying on an outsole and permanently securing the same to said upper and said shank piece and then removing said last and said backing piece.
